(57) **CLAIM**

The ornamental design for a vehicle fender flare, as shown and described.

DESCRIPTION

FIG. 1 illustrates a perspective view of a vehicle fender flare employing an ornamental design in accordance with the present invention;

FIG. 2 is a front view of the vehicle fender flare of FIG. 1; FIG. 3 is a back view of the vehicle fender flare of FIG. 1; FIG. 4 is a left side view of the vehicle fender flare of FIG. 1;

FIG. 5 is a right side view of the vehicle fender flare of FIG. 1;

FIG. 6 is a top view of the vehicle fender flare of FIG. 1; and, FIG. 7 is a bottom view of the vehicle fender flare of FIG. 1.

In the drawings, the broken lines depict portions of the vehicle fender flare that form no part of the claimed design.

1 Claim, 7 Drawing Sheets
